UNITED STATES PATENT OFFICE.

ISAAC C. THOMPSON, OF WOLFBOROUGH, NEW HAMPSHIRE.

ROOFING FOR BUILDINGS.

SPECIFICATION forming part of Letters Patent No. 456,971, dated August 4, 1891.

Application filed February 16, 1891. Serial No. 381,609. (No model.)

To all whom it may concern:

Be it known that I, ISAAC C. THOMPSON, of 5
Wolfborough, in the county of Carroll, State
of New Hampshire, have invented certain new
and useful Improvements in Roofing for Buildings,
of which the following is a description
sufficiently full, clear, and exact to enable any
person skilled in the art or science to which
said invention appertains to make and use
10 the same, reference being had to the accom-
panying drawings, forming part of this speci-
fication, in which—

Figure 1 is a perspective view of a section
of my improved roofing; Fig. 2, a sectional
15 view showing my improved roofing in posi-
tion on the rafters, and Fig. 3 a like view
illustrating a modification.

Like letters of reference indicate corre-
sponding parts in the different figures of the
20 drawings.

My invention relates especially to roofing
constructed of planks or boards, whereby the
use of shingles, ordinary boarding, and pur-
lins may be obviated; and it consists in cer-
25 tain novel features, hereinafter fully set forth
and claimed, the object being to produce a
simple, cheap, and effective article of this
character.

The nature and operation of the improve-
30 ment will be readily understood by all con-
versant with such matters from the following
explanation: The roofing B is formed from a
series of boards or planks b, arranged with
their edges obtruding and secured to cross
35 ties or braces d. In the upper face of each
board b, near each edge, is formed a longitudi-
nally-arranged slot f, inclined vertically at an
angle of about forty-five degrees to the plane
of the surface of said boards. A metallic
40 strip g, A-shaped in cross-section, is inserted
in the slots of adjacent boards, as shown in
Fig. 1, forming a water-tight joint. A section
of roofing thus formed and of a length deter-
mined by the length of the braces d is laid

directly onto the rafters h, said braces being 45
disposed at right angles to the rafters and se-
cured thereto by any suitable means. The
braces substitute for the boarding or lathing
to which shingles are ordinarily attached and
obviate the necessity of using purlins i. A 50
succeeding section is then laid with its lower
edge overlapping the upper edge of said first
section after the manner of shingles. When
the pitch of the roof is slight, I insert a ver-
tical laterally-arranged metallic binding-plate 55
k in suitable grooves in the overlapping edges
of the roof-sections, forming a tight joint,
which prevents the water from "backing up"
under said sections. Where purlin is used,
as in Fig. 3, the braces d may be omitted and 60
the boards b secured directly to the rafters
and purlin. By forming the grooves f in-
clined, as described, the water is prevented
from working around the plate g and into the
joint between the boards, as might occur when 65
the grooves are vertical.

Having thus explained my invention, what
I claim is—

1. Roofing for buildings, formed in sections,
comprising boards disposed in the same plane
and connected at their edges by longitudi-
nally-arranged A-shaped plates inserted in
correspondingly-arranged grooves in said
70 boards, said sections being disposed to over-
lap and connected by a vertical binding-plate
75 inserted in lateral grooves in their overlapped
portions.

2. The roofing B, formed in overlapping
sections, each section comprising boards b,
grooved at f and secured to braces d, metallic 80
A-shaped strips g in said grooves, and verti-
cal binding-strips k, inserted in lateral grooves
in said overlapping portions.

ISAAC C. THOMPSON.
